(57) CLAIM

The ornamental design for a garment, as shown and described.

DESCRIPTION

FIG. 1 is a front left perspective view of a garment showing my new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof; and,

FIG. 7 is a bottom plan view thereof.

The short evenly spaced broken lines depict stitching which forms part of the claimed design. The long, evenly spaced broken lines that outline a partial human figure assist in illustrating how the garment may appear when in a position of use, and form no part of the claimed design. The short broken lines arranged near the rear side of the garment at the center bottom of the garment depict a feature of the article that forms no part of the claimed design.
